NORMAN LEA, OF COVENTRY, AND JOHN REE, OF PINNER, ENGLAND.

ELECTROMAGNETIC-WAVE SIGNALING SYSTEM.

Application filed September 26, 1919. Serial No. 326,693.

To all whom it may concern:

Be it known that we, NORMAN LEA and JOHN REE, both subjects of the King of Great Britain, residing, respectively, in 5 Coventry, England, and Pinner, England, have jointly invented certain new and useful Improvements in Electromagnetic-Wave Signaling Systems, of which the following is a specification.

10 The present invention relates to improvements in methods for controlling continuous or semi-continuous electromagnetic wave transmitters employing oscillating valves, by means of a Morse key or interrupter or 15 both.

It is sometimes desired to operate such a transmitter so that no oscillations of any kind are produced when the circuit is broken by means of the key or interrupter.

20 A method is known whereby the connections of the grid leak across the grid condenser are made and broken by means of a Morse key or otherwise.

The objection to this method is that although continuous oscillations are not maintained in the aerial circuit when the grid leak connections are broken on the key being raised, periodic trains of oscillations are induced in the aerial circuit.

25 In order to overcome the periodic trains of oscillations described in the above arrangement it is usual to interrupt the main high tension supply. The interruption of the high tension supply causes arcing across the controlling contacts and the object of 30 this invention is to provide means whereby such high tension supply may be interrupted without causing arcing to take place at such contacts.

35 According to this invention the grid or control element is connected conductively and permanently with the negative lead of the high tension supply, and the key or interrupter is interposed between the high tension supply leads in a circuit including the grid and the filament of the valve.

40 By this arrangement the potential drop across the interrupting contacts at the moment of break is included in the grid circuit. This has the effect of causing an increase of the mean negative potential of the grid and thereby tends to reduce the current 45 in the anode circuit, and hence the current flowing from the high tension supply through the interrupting contacts.

One arrangement according to this in-

vention is shown on the accompanying drawing, but the invention may be used in conjunction with any known means for maintaining the grid of the oscillatory valve 60 at a mean negative potential with respect to the filament, such as a battery or condenser and grid "leak".

In the drawing a Morse key is shown as the interrupter and the key 1 is placed between the filament 2 and the negative lead 3 of the high tension supply. The reaction inductance coil 4 is connected with the grid 5, whilst the anode 6 is connected with a closed oscillatory circuit comprising an inductance 7 and condenser 8. The anode condenser 9 is placed as shown between the filament 2 and the positive lead 10 of the high tension supply.

Having thus described the nature of the 75 said invention and the best means we know of carrying the same into practical effect, we claim:

1. In an electromagnetic wave transmitter employing an oscillatory valve, means for 80 controlling the trains of oscillations comprising a permanent conductive connection between the control element of the valve and the negative lead of the high tension supply and a circuit interrupting device interposed 85 in a conductor connecting the said negative lead and the filament of the valve.

2. In an electromagnetic wave transmitter employing an oscillatory valve, means for 90 controlling the trains of oscillations comprising a permanent conductive connection between the control element of the valve and the negative lead of the high tension supply, a condenser interposed between the positive lead of the high tension supply and the valve 95 filament and a circuit interrupting device interposed in a conductor connecting the negative lead of the high tension supply and the filament.

3. In an electromagnetic wave transmitter 100 employing an oscillatory valve, means for controlling the trains of oscillations comprising a permanent conductive connection between the control element of the valve and the negative lead of the high tension supply, 105 and a circuit interrupting device interposed between the high tension supply leads in a circuit including the grid and the filament of the valve.

4. In an electromagnetic wave transmitter 110 employing an oscillatory valve, means for controlling the trains of oscillations com-

prising a permanent conductive connection between the control element of the valve and the negative lead of the high tension supply, and a circuit interrupting device interposed 5 in series with a condenser between the high tension supply leads.

5. In an electromagnetic wave transmitter employing an oscillatory valve, means for controlling the trains of oscillations, comprising a permanent conductive connection 10 between the control element of the valve and the negative lead of the high tension supply, a condenser and a circuit interrupting device interposed in a conductor connecting the high tension supply leads and a 15 permanent connection between the valve filament and a point of the said conductor intermediate between the condenser and the circuit interrupting device.
20. 6. In an electromagnetic wave transmitter employing an oscillatory valve, means for controlling the trains of oscillations comprising a permanent conductive connection between the control element of the valve and the negative lead of the high tension supply, 25

and a circuit interrupting device interposed between the high tension supply leads in a circuit including the grid and the filament of the valve, said circuit interrupting device being adapted, when closed, to connect the 30 negative lead of the high tension supply with the said condenser.

7. In an electromagnetic wave transmitter employing an oscillatory valve, means for controlling the trains of oscillations comprising a permanent conductive connection 35 between the control element of the valve and the negative lead of the high tension supply with the filament of the valve, a condenser directly interposed between the point 40 of connection of filament and said conductor and the positive lead of the high tension supply and an oscillatory circuit connected between the point of connection of the said condenser with the positive high tension 45 lead and the anode of the valve.

In testimony whereof we have signed our names to this specification.

NORMAN LEA.
JOHN REE.
